(57) **CLAIM**

The ornamental design for a wrench torque adapter, as shown and described.

DESCRIPTION

FIG. 1 is a perspective, front, left side view of a wrench torque adapter according to the present invention;

FIG. 2 is an environmental, perspective, front, right side view of the wrench torque adapter of FIG. 1, wherein the adapter is engaged with a ratchet;

FIG. 3 is an environmental, perspective, front, right side view of the wrench torque adapter of FIG. 1, wherein the adapter is engaged with a ratchet and a wrench;

FIG. 4 is a right side view of the wrench torque adapter of FIG. 1;

FIG. 5 is a left side view of the wrench torque adapter of FIG. 1;

FIG. 6 is a front view of the wrench torque adapter of FIG. 1;

FIG. 7 is a rear view of the wrench torque adapter of FIG. 1;

FIG. 8 is a top view of the wrench torque adapter of FIG. 1; and,

FIG. 9 is a bottom view of the wrench torque adapter of FIG. 1.

The broken lines shown in the drawing views are included for illustrative purposes only and form no part of the claimed design.
